UNITED STATES PATENT OFFICE

166,615

PORTABLE OUTDOOR CLOTHES RACK

Duane S. Loughlin, Auburn, Calif.

Application December 13, 1951, Serial No. 17,717

Term of patent 14 years

(Cl. D33—8)

To all whom it may concern:

Be it known that I, Duane S. Loughlin, a citizen of the United States, residing at Auburn, in the county of Placer, and State of California, have invented a new, original, and ornamental Design for a Portable Outdoor Clothes Rack, of which the following is a specification, reference being had to the accompanying drawing, forming part thereof.

I claim:

The ornamental design for a portable outdoor clothes rack, as shown.

DUANE S. LOUGHLIN.
